TRACTOR BULLDOZER

Thomas R. Paulsen, South Milwaukee, Wis., assignor to Bucyrus-Erie Company, South Milwaukee, Wis., a corporation of Delaware

Application December 17, 1937, Serial No. 180,292

2 Claims. (Cl. 60—52)

My invention relates to new and useful improvements in bulldozers, and more particularly to that type of bulldozer in which the scraping blade is pushed ahead of a tractor.

Such devices are usually designed for attachment to some conventional type of tractor. They consist of a blade, two arms pivoted on the tractor for pushing the blade, and means to raise and lower either arm with a certain degree of independence from the lowering and raising of the other arm. The last-mentioned means usually consists of one or two hydraulic cylinders actuated by a pump driven by the engine of the tractor.

If two such cylinders are used, it is convenient to have them controlled by a single control-valve, but this interferes with the flexibility of the moving parts.

Accordingly it is the principal object of my invention to provide means whereby the average position of the two pistons is controlled by the valve, while leaving the pistons free to reciprocate compensatingly in all positions; and whereby whenever the two pistons are both shifted either to extreme out or extreme in position, both pistons will speedily assume an average position just short of their former extreme position, and thus become free to reciprocate compensatingly as already stated.

In addition to my principal object, above stated, I have worked out a number of novel and useful details, which will be readily evident as the description progresses.

My invention consists in the novel parts and in the combination and arrangement thereof, which are defined in the appended claims, and of which one embodiment is exemplified in the accompanying drawings, which are hereinafter particularly described and explained.

Throughout the description, the same reference number is applied to the same member or to similar members.

Figure 1 is a plan view of a tractor and bulldozer embodying my invention.

Figure 2 is a side elevation of this same tractor and bulldozer.

Figure 3 is a longitudinal section of one of my cylinders.

Figures 4 and 5 are comparative figures, somewhat conventionalized, to illustrate the function performed by a certain fluid by-pass, which forms one of the elements of my invention.

Referring now to Figures 1 and 2, we see that 11 is a conventional tractor, mounted on creeping traction 12. These creeping traction elements are

pivoted on propelling shaft 13, and their front ends have considerable freedom to rise and fall to conform to unevenness of the ground.

Pivoted to each traction element 12 at 14 is a forwardly projecting arm 15. These arms support 5 and impel a scraper blade 16.

On each side of the tractor there is a link 17 pivoted to the rear of the tractor at 18, and a link 19 pivoted to the creeping traction at 20. These two links are pivoted together at 21, and at this 10 point is also pivoted the elbow of a bell-crank 22.

The front end of each bell-crank supports one side of the blade 16 through a link 23.

There are two cylinders 24, each pivoted at 25 on one of the links 17. The piston rod 26 of each 15 cylinder is pivoted at 27 to the short arm of the bell-crank 22.

The rear ends of the two cylinders are connected by a pipe 28, from which a pipe 29 leads to a control-valve 30. The front ends of the two cylinders are similarly connected by a pipe 31, from which a pipe 32 leads to the control-valve already mentioned. Thus free intercommunication between the two cylinders is maintained, regardless of the valve-setting. This is what I 25 mean in the claims by "freely connecting together."

The control-valve may be of any conventional design, the details of which are not shown as they form no part of my invention. But the valve 30 should have four positions, namely: (1) to pump from the rear of the cylinders into the front, and thus retract the pistons; (2) to pump from the front of the cylinders into the rear, and thus thrust the pistons out; (3) to close both pipe 29 and pipe 32, and thus hold the pistons; and (4) to open pipe 29 to pipe 32, and thus permit free floating of the pistons.

From the valve a pressure pipe 33 and a suction pipe 34 lead to a pump 35, actuated in any conventional manner by the main engine of the tractor. From a fluid tank 36, there runs to suction pipe 34, a pipe 37 with a check valve 38, for the purpose of keeping the system always filled 45 with fluid. From the suction pipe 34 to the tank 36, there runs a pipe 44 with a pressure relief valve 45, to permit compensation for the space occupied by the piston rods 26 within the cylinders 24 when the pistons are being retracted, and yet hold them 50 against unintended retracting.

The connection of blade 16 to arms 15 is almost rigid, for the purpose of holding the blade at all times in virtual parallelism with axle 13; points 14 being sufficiently close to the axle 13 for this purpose. But the relative rise and fall 55

of points 21, as the two traction elements encounter uneven ground, would tend to raise the two links 23 an unequal amount, inconsistent with the quasi-rigidity of the quadrilateral formed by the blade 16, the arms 15, and the axle 13. Accordingly we must either sacrifice this desirable quasi-rigidity, or devise some means to compensate for the relative rise and fall of points 21. I have chosen the latter alternative.

10 Accordingly (see Figure 4) I have freely interconnected the front end of my two cylinders by pipe 31, and have freely connected the rear end of my two cylinders by pipe 28.

In Figures 4 and 5, cross-bar 39 does not represent any actual part of my apparatus. It is merely diagrammatic, to illustrate the compensating reciprocation of my two pistons which my invention permits.

Let us assume that my two pistons 40 are in 20 the mid position illustrated in Figure 4, and that some condition encountered by cross-bar 39 tends to tilt it into the dotted-line position. The shift of the pistons to their dotted-line positions, to permit this, is in turn permitted by the free flow 25 of fluid from the rear of the upper cylinder through pipe 28 to the rear of the lower cylinder, and the free flow of fluid from the front of the lower cylinder through pipe 31 to the front of the upper cylinder. But note that the mid point 30 of cross-bar 39 is still firmly held.

Now assume that the pistons are at their extreme rearward position, as shown in Figure 5, and some condition tends to tilt the cross-bar 39. This would not be possible, were it not for the 35 further and most important feature of my invention.

Neither piston can move further to the rear, but either one of them can move to the front, as follows. Let us assume that the tendency 40 is for the lower piston to move forwards. The fluid to the front of it passes through pipe 31 into the front of the upper cylinder, thus forcing fluid through the by-pass 41 around the piston 40 of that cylinder; thence through pipe 28 into 45 the rear of the lower cylinder, thus permitting the piston of that cylinder and hence the cross-bar 39 to assume their dotted-line positions. It might be thought that this situation would leave the lower piston of Figure 5 free to move 50 back and forth the whole length of the cylinder. It would, were it not for the quasi-rigidity of the U formed by the arms 15 and blade 16. This quasi-rigidity has already been referred to. Due to this quasi-rigidity, a slight rising of the right 55 tread will pull out the lower piston only a slight part of its potential travel, say to the dotted position shown in Figure 5. When the treads return to parallelism, and the piston tends to return to its full-line position, the device will work as in 60 Figure 4, and the two pistons will assume an average position half way between the full-line and dotted positions in the lower cylinder of Figure 5. The cylinders are so proportioned and placed that this nearly all-in position raises the 65 blade as high as is necessary.

Similarly if the tilting tendency were the opposite.

By-pass 42 similarly permits tilting when the pistons are in their extreme forward positions.

It is to be noted, more particularly from Figure 3, that each of the by-passes is closed by a check-valve 43, so as to prevent flow in the wrong direction; flow in the wrong direction would permit the sudden bumping of the pistons against the cylinder-heads, upon arriving at extreme position. It is also to be noted that each by-pass is just barely long enough to route the fluid 10 around the piston when the piston is in extreme position; more than this would render the device unnecessarily unstable.

Having now described and illustrated one form 15 of my invention, I wish it to be understood that my invention is not to be limited to the specific form or arrangement of parts hereinbefore described, except insofar as such limitations are specified in the appended claims.

I claim:

1. In combination: two fluid pressure cylinders; pistons therein; piston rods for the pistons; a fluid pressure pump, to supply fluid to the cylinders; control means interposed between the pump and the cylinders to control flow of fluid to and from the two cylinders jointly; a pipe freely connecting together the front ends of the two cylinders when the control means is set to disconnect the pump from the cylinders; a pipe freely connecting together the rear ends 30 of the two cylinders when the control means is set to disconnect the pump from the cylinders; at each end of each cylinder a by-pass to pass fluid around the piston when in extreme position at that end of the cylinder; a check-valve in 35 such by-pass, so as to permit flow only toward the adjacent end of the cylinder; and an actuated element connected to the outer ends of the two piston rods for limited movement relative to the piston rods; whereby limited compensating relative movement of the pistons is rendered possible at either end of their stroke.

2. In combination: two fluid pressure cylinders; pistons therein, piston rods for the pistons; a fluid pressure pump, to supply fluid to the cylinders; control means interposed between the pump and the cylinders to control flow of fluid to and from the cylinders, so as selectively to thrust, retract, and hold the two pistons jointly; a pipe freely connecting together the front ends of the two cylinders when the control means is set to hold; a pipe freely connecting together the rear ends of the two cylinders when the control means is set to hold; at one end of one cylinder and at the corresponding end of the other cylinder, a by-pass to pass fluid around the piston when in extreme position; a check-valve in such by-pass, so as to permit flow only toward the adjacent end of the cylinder; and an actuated element connected to the outer ends of the two piston- 50 rods for limited movement relative to the piston rods; whereby limited compensating relative movement of the pistons is rendered possible at one end of their stroke.

THOMAS R. PAULSEN.
